TEARING MEANS FOR WRAPPERS OF CELLOPHANE AND THE LIKE

Bruno Olsson, St. George, N. Y.

Application November 9, 1937, Serial No. 173,553

5 Claims. (Cl. 229—51)

The object of the present invention is to provide means for tearing away a top end section of a wrapper enclosing cigarettes or other material so as to expose an opening through which the cigarettes or other articles may be removed. The object of the invention is to provide means of such character adapted to tear through a plurality of folded plies of material which have such substantial resistance to the tearing arrangements known in the art as to create a problem which is overcome by the present invention.

The specific object of the invention will be described with reference to the accompanying drawings, in which—

Figure 1 is a plan view of a section of cellophane or other wrapping material, showing the cutting of a window therein.

Figure 2 is a plan view showing a window covering strip.

Figure 3 is a plan view showing the application of the covering strip on the window, the boundaries of the latter being shown in dotted lines.

Figure 4 is a plan view of one lateral section of a wrapping sheet prior to folding, certain lines of fold being shown creased and said section having applied thereto a tearing strip in angularly bent formation.

Figure 5 is a plan view of the tearing strip before folding or bending.

Figure 6 is a perspective view of the wrapper in folded position about the box before the end closing folds are formed prior to the application of the transparent cellulosic sheet.

Figure 7 is a view similar to Figure 6, showing the completely folded package.

Figure 8 is a plan view of the structure shown in Figure 7 after the application of the transparent cellulosic sheet, but the window covering not having been used.

Figure 9 is a view similar to Figure 8, showing the window cover.

Figure 10 is a schematic perspective view showing the action of the tearing means in removing the rectangular section from the top end of the cigarette package.

Figure 11 is a fragmentary plan view showing a wrapper of transparent cellulosic material having the central section removed and having window cuts at opposite areas thereof.

Figure 12 is a view showing the application of the window by folding the transparent cellulosic sheet about a package.

Figure 13 is a view similar to Figure 12 showing the window cover piece in position.

Figure 14 is a view similar to Figure 13, showing by top plan view the completely formed package.

Figure 15 is a modified form of the transparent cellulosic sheet broken away at the center, having a window and a window covering lip.

Figure 16 is a top plan view of the sheet in folded position showing the covering of the window.

Figure 17 is a top plan view of the completed packaging using the structure of Figure 15.

Referring to the drawings, I have shown in Figure 1 a fragment of a transparent cellulose wrapper C formed with an opening at 3, which is later to be applied to the package shown in partially folded form in Figure 6. In that figure the folded sheet material of the package is indicated at O. P. It will customarily be formed of two or more layers as, for example, foil and paper, and the position of the inner layer is indicated at I. P. It will be noted that at the top of the package is an upwardly extending section adapted to be folded inwardly and then downwardly to cover the open top of the package. On the inner layer I. P. there is bent or folded a tearing strip R which may be of cellulosic or other material in the form of a tape or it may be made of a cord.

The tearing strip is so folded as to have a projecting end which continues down to the point 1 (Figure 4) where it meets the edge of the inner surface I. P. and then extends further downwardly to the point 8 where it is turned at right angles and crosses the lines of vertical fold at 9 and 10, then extending to the point 11 where it is turned upwardly at right angles and terminates at the point 12.

When the main wrapper member or members are in position for folding down of the projected top section, the structure will be in the form shown in Figure 6, and when that top area is folded down the structure will be in accordance with that shown in Figure 7.

At S I have shown a usual revenue stamp applied to cigarette packages. It will be noted that the projected end of the tape R lies adjacent the revenue stamp, although in practice, a part of the tape may lie under the stamp so that when it is pulled upwardly to tear out a rectangular opening in the wrapper, the stamp will be torn.

In the use of the transparent cellulose outer wrapping sheet, it may be applied simultaneously

with the inner wrapping sheet, or sheets, as shown in Figure 6, and hence the projected end of the tape R will lie outwardly from the top edge of the sheet and will project in the manner shown in Figure 8. Inasmuch as it is desired that the cellulosic material entirely enclose the inner package layer or layers, I apply to the opening 3 a covering or cap member 4 of like material. This is done preferably before the package is formed and the revenue stamp will overlie a side margin of the cap 4 so that when it is torn loose by the pulling of the tape the stamp will be torn (note Figure 9 wherein the left-hand margin of the cap 4 is shown under the stamp S). It will be noted that the tearing strip bounds the opening 3 and therefore in the pull of the tape the cellulose offers minimum resistance against the tearing action, the cap 4 being readily pulled away by reason of the fact that its adhesive bond to the cellulose will offer less resistance than a corresponding integral area of cellulose sheet.

Although in Figure 1 I have shown the opening at 3 as stamped out of an inner area of the cellulose sheet, the opening may be formed by incut sections at the ends of the sheet as shown in Figure 11. When the sheet is folded over in the manner shown in Figure 12, these incut areas will lie in register to form an opening and to receive a cap 4 identical with that shown in Figure 2.

In the figures, the full line 16 indicates the overlying edge of the cellulosic sheet at the top of the package and 17 the underlying edge of the opposite margin of the folded sheet.

The further modification as shown in Figures 15 to 17 inclusive, eliminates the necessity for a separate cap 4. To this end, one margin of the cellulose sheet is cut away at 15 and the opposite edge is formed with a larger semi-annular projection 14 terminating at the points a and b which may be slight cuts into the body of the cellulose sheet. When the cellulose sheet is applied, the projection 14 will lie over and will cover the opening 15 and the tape will readily tear the cellulose sheet at the sides of the projection 14, particularly in view of the small cuts at a and b.

In the drawings I have shown the opaque wrapper O. P. in full lines inasmuch as the cellulose outer covering will be transparent. In the various figures only the folded over edge 16 of the cellulose sheet and the cap 4 have been shown in full lines.

It will be understood that various modifications may be made in the embodiments illustrated in the drawings without departing from the spirit of the invention.

Having described my invention, what I claim and desire to secure by Letters Patent, is as follows:—

1. In window forming means for packages comprising an inner folded wrapper and an outer transparent cellulosic covering sheet, a tearing strip folded in rectangular formation to bound a corresponding portion at the inside of the upper folded laps of the inner wrapper, an end of the strip being projected outwardly from the package and an outermost wrapping sheet of transparent cellulosic material having an area cut away to form a window adjacent said rectangular formation of the strip, and a covering cap for said window.

2. In window forming means for packages comprising an inner folded wrapper and an outer transparent cellulosic covering sheet, a tearing strip folded in rectangular formation to bound a corresponding portion at the inside of the upper folded laps of the inner wrapper, an end of the strip being projected outwardly from the package and an outermost wrapping sheet of transparent cellulosic material having an area cut away within its margin to form a window and a covering cap secured by adhesive to the area of the sheet at the sides of said cut away area, said cap lying over said rectangular formation of the strip.

3. In window forming means for packages comprising an inner folded wrapper and an outer transparent cellulosic covering sheet, a tearing strip folded in rectangular formation to bound a corresponding portion at the inside of the upper folded laps of the inner wrapper, an end of the strip being projected outwardly from the package and an outermost wrapping sheet of transparent cellulosic material having an area cut away to form a window adjacent said rectangular formation of the strip, a sealing stamp strip applied to the top of the wrapper, and a covering cap for the window having a marginal area projected under the sealing stamp strip.

4. Window forming means for packages constructed in accordance with claim 1, in which the window is formed by opposed cut away marginal areas of a sheet of transparent cellulosic material.

5. Window forming means for packages constructed in accordance with claim 1, in which the sheet of transparent cellulosic material is formed at one margin with a cut away area and is formed at the opposite margin with a projecting lip to form a covering cap for said cut away area when the sheet is in folded position upon the inner wrapper.

BRUNO OLSSON.
